Primary Examiner — Elizabeth A. Albert*(74) Attorney, Agent, or Firm* — Avyno Law P.C.(57) **CLAIM**

I claim the ornamental design for a dual-sided writing board, as shown and described.

DESCRIPTION

FIG. 1 is a front perspective view of a dual-sided writing board of the present invention.

FIG. 2 is a front elevation view of the dual-sided writing board of FIG. 1.

FIG. 3 is a rear elevation view of the dual-sided writing board of FIG. 1.

FIG. 4 is a left side elevation view of the dual-sided writing board of FIG. 1.

FIG. 5 is a right side elevation view of the dual-sided writing board of FIG. 1.

FIG. 6 is a top plan view of the dual-sided writing board of FIG. 1.

FIG. 7 is a bottom plan view of the dual-sided writing board of FIG. 1.

FIG. 8 is a front perspective view of a dual-sided writing board of the present invention shown in use with the support stand extended away from the front writing surface; and, FIG. 9 is a rear perspective view of a dual-sided writing board of the present invention shown in use with the support stand extended away from the rear writing surface.

In the drawings, the broken lines depict portions of the dual-sided writing board that form no part of the claimed design.
